UNITED STATES PATENT OFFICE.

MILTON MARX, OF LA GRANGE, ILLINOIS.

PACKING-RACK.

1,320,335.

Specification of Letters Patent.

Patented Oct. 28, 1919.

Application filed March 26, 1918. Serial No. 224,915.

To all whom it may concern:

Be it known that I, MILTON MARX, a citizen of the United States, and a resident of the city of La Grange, county of Cook, 5 State of Illinois, have made a new and useful invention—to wit, Improvements in Packing-Racks; and I do hereby declare the following to be a full, clear, concise, and exact description of the same.

10 The invention relates particularly to racks for assembling miscellaneous articles for insertion into inclosing containers.

Among the objects of the invention are to provide a rack wherein can be assembled 15 miscellaneous articles within predetermined dimensions, in graduated sizes to fit fabricated containers in various sizes to fit the aggregation of articles whereby the packing of the same is facilitated.

20 Another object is to save time and guard against the injury of such articles being packed. Other objects and advantages will appear as this description progresses.

In this specification and the annexed 25 drawings, the invention is illustrated in the form considered to be the best, but it is to be understood that the invention is not limited to such form, because it may be embodied in other forms, and it is also to be understood that in and by the claims following the description, it is desired to cover 30 the invention in whatever form it may be embodied.

In the accompanying one sheet of drawings:

Figure 1 is a perspective view from in front of a packing rack constructed in accordance with this invention.

Fig. 2 is a plan view in perspective of the 40 same from above and to the rear, having a container in position thereon.

Fig. 3 is a perspective view from in front of the same.

Fig. 4 is a perspective modification of the 45 invention.

Fig. 5 is a front elevation of Fig. 4 illustrating the manner in which the edges of the slots are formed.

In detail the construction illustrated in 50 the drawings includes a rack preferably composed of sheet metal, having the solid bottom 1, with end portions rising perpendicularly thereto and slotted as at 2, 3, 4 and 5, dividing the ends into the divisions

6, 7, 8, 9 and 10, in horizontal alignment 55 at opposite ends of the rack. The back of the rack consists of a plate 11 perpendicular to the bottom 1 and having a central opening 12 dividing the back into the plates 13 and 14. The whole rack is preferably 60 composed of an integral piece of sheet metal, such as steel, properly blanked and bent to take the general form illustrated in the drawing. Such a construction is within the province of the sheet metal 65 worker, and the design may be variously modified to accomplish economy in production and it may be made up of any number of independent parts joined by riveting, welding, or otherwise, all of which is within 70 the purview of this invention.

It is necessary that this rack be raised above the surface of the table 15 to permit the introduction of a portion of the container thereunder. For this purpose the 75 rack is supported on the offset legs 15' and 16, fixed to the back plates 13 and 14 and having the feet 17 and 18 fixed to the surface of the table 15, in such a manner that the legs 15' and 16 support the total weight 80 of the articles assembled in the rack.

In this present embodiment the rack is designed particularly to receive laundered articles of clothing to be packed in modern steam laundries, although I do not wish to 85 be understood as limiting this invention to that use, as it is obviously applicable to various other uses.

The tops of the strip from 6 to 10 are preferably respectively 2, 3½, 5, 7, and 9 90 inches from the bottom 1, and the rack is about 18 inches long by 9 inches wide. Into the rack is packed such articles as starched and folded shirts and other articles of laundry that come from the processing machines, folded to conventional lengths, in segregated quantities representing each customer's quota. The wrapper soon learns to stack these articles in the most efficient manner to conserve space within the appropriate 100 sizes of the fabricated containers. If the stack of articles within the rack rises to the slot 4, as in Fig. 2, the container of that size is selected and applied by having its cover 19 and attached backing 20 slid under the bottom 1 of the rack, and with its top 21 slid into the slot 4, with the sides 22 and 23 inclosing the strips 6, 7 and 8 at the 105

ends, and the back 24 extending across the front of the rack. These containers are fabricated in the form of paper bags or cartons, supplied in folded or collapsed shape 5 adapted for the purpose. Thus assembled on the rack, the container entirely incloses the bundle of laundry within the rack. With his hand, the wrapper presses against the bundle through the gap 12 in the back, 10 forcing the container off the rack with the contents of the rack therein. The cover 19 is then closed over the top of the bundle, and pasted or otherwise secured, or the whole pack is wrapped with string, if its 15 weight necessitates. The same operation applies where the bundle entirely fills the rack or only a thickness equal to the sides 6—6. It is good practice to increase the strength of the containers relative to their 20 sizes, ranging from light paper bags for No. 6, to pulp paper cartons for No. 10, thus avoiding the necessity for the use of string, which in addition to being costly is also a time consumer.

25 Figs. 4 and 5 are modifications of Fig. 1 showing the sides 26 and 27 slotted to form the divisions 6', 7', 8', 9' and 10', with the opening 12' located in the center of the end wall 28. This rack is raised above the table similarly to Fig. 1 and is supported by the offset legs 30 and 31 fastened to the floor by screws 32 and 33 each leg formed respectively from a single piece of strap iron 34 and 35 secured along the full height 30 of the end wall 28 as at 37 and 38 and bent back from a point near the upper edge of the rack to form the supporting arms 40 and 41, secured to the table by the screws 42 and 43. This supporting construction is 35 desirable where the rack has a length greater than its width.

The upper edges bordering the divisions 6', 7', 8', 9' and 10' are turned over as at 44, 45, 46, 47 and 48 to form smooth edges 45 permitting the container to be slipped freely onto the parallel sides of the rack and over the stacked articles in the rack as previously described. It will be noted that the free ends of the members 6', 7', 8', 9' and 10' are beveled as at 49 to facilitate application of the container.

What I claim and desire to secure by Letters Patent is:

1. A packing rack of the kind described including a box like structure to receive the articles to be packed having an open front and slotted end walls, for the purposes specified. 55

2. A packing rack of the kind described including a box like structure to receive the 60 articles to be packed having an open front; a partially open back; and slotted end wall, for the purposes specified.

3. A packing rack of the kind described including a boxlike structure to receive the 65 articles to be packed having an open front; a partially open back; and end walls slotted at graduated heights for the purposes specified.

4. A packing rack of the kind described 70 including a boxlike structure to receive the articles to be packed having an open front; a back plate with a hand gap therein; and slotted end walls for the purposes specified.

5. A packing rack of the kind described 75 including a boxlike container having an open front and slotted end walls; and means for supporting said container above a table surface, leaving the container with an unobstructed front end adapted to have the 80 walls of a bag or carton inserted selectively in said slots and under the container, whereby the contents of the latter may be removed into the former, as set forth.

6. A packing rack of the kind described 85 including a boxlike container having an open front and slotted end walls; and legs fixed to back of the container and extending outward and downward therefrom.

7. A packing rack of the kind described 90 including a boxlike container having an open front; a partially open back; and legs fixed to said back and extending obliquely outward and downward from near the rear corners of said rack. 95

In testimony whereof, I have hereunto set my hand at San Francisco, California, this 28th day of February 1918.

MILTON MARX.

In presence of—

LINCOLN JOHNSON,
A. J. HENRY.
